COKE-OVEN.

1,154,298.

Specification of Letters Patent. Patented Sept. 21, 1915.

Application filed June 13, 1913. Serial No. 773,418.

To all whom it may concern:

Be it known that I, KARL ELLINGEN, a subject of the Emperor of Germany, residing at Farnstrasse No. 62, Bochum, Germany, have invented certain new and useful Improvements in Coke-Ovens, of which the following is a specification.

This invention relates to coke-ovens, and more especially to that type comprising horizontal coking chambers having side heating walls in which vertical heating flues are arranged.

The object is to provide a simple, practical and advantageous construction and arrangement whereby two kinds of fuel gases can be used, either independently or in combination and in variable proportions. The gases which it is thus proposed to make use of are: gas of relatively low calorific value, such as producer gas or gas from a shaft furnace, and gas of relatively high calorific value, such as gas from the charge that is being coked in the coke-oven. Fuel gas of the first kind, it may be stated, requires preheating, whereas the gas coming from a coke-oven requires no preheating.

The invention resides more particularly in a construction wherein the heating flue may be supplied from a passage for heating gas of low calorific value, or from a tubular member constituting a conduit for gas of higher calorific value, such as coke-oven gas, the said tubular member being adjustable so as to serve as a valve for controlling the admission of low calorific gas and being itself provided with valve means for controlling the amount of high calorific gas supplied. Thus the oven can be operated with low calorific gas alone, with high calorific gas alone, or with a combination of both, and in any case the amount of either or both of the gases is variable at will. It is evident that with an organization of this character exact and complete control is obtainable, while at the same time a dual fuel supply is made available.

The accompanying drawings illustrate a preferred mode of carrying the invention into effect, and the essentials thereof will be found pointed out more particularly in the appended claims.

In the said drawings: Figure 1 is a ver-

tical transverse section through a portion of a coke-oven structure; and Fig. 2 is a vertical section, on an enlarged scale, through the means for supplying the high calorific gas, which means constitutes also a valve mechanism for regulating the flow of the low calorific gas.

It will be understood that the illustration is only fragmentary and to an extent diagrammatic.

The horizontal coking chambers are indicated at *a*. As is customary, these are provided with side heating walls *b*, in which are formed vertical heating flues *c*, which may extend throughout the length of the coking chambers or be subdivided into groups of flues in any desired or customary manner. The outlets from these flues have not been specifically illustrated, because they may be of any appropriate character as far as the present invention is concerned. Below the coking chambers in the foundations of the structure there are tunnels *t*. These are preferably located beneath every other coking chamber, so that the apparatus in each tunnel serves the heating flues of two side heating walls.

Means are provided for supplying each heating flue *c* with air for combustion and fuel gas of one kind. Preferably both of these supplies communicate with the heating or combustion flues at or adjacent their bottoms. In the particular construction shown there is a longitudinally-extending gas passage *f* and a longitudinally-extending air passage *h* at opposite sides of the lower portion of each combustion flue, and beneath the latter there is a longitudinally-extending fuel gas channel *e*, which channel communicates with the corresponding flue by means of a series of nozzle openings or twyvers *d*. The air passages *h* communicate with the lower part of the combustion flue by lateral openings *i*, while the fuel gas passage *f* communicates with the gas channel *e* by lateral openings *g*. It will be understood that the number and spacing of the openings *i* and *g* will be determined by the particular conditions of different cases, and, similarly, the number and size of the twyver openings *d* may be varied. The gas passages *f* supply the combustion flues with fuel

gas of low calorific value and are accordingly provided with appropriate connections (not shown) with the usual regenerators, which, as will be understood by those skilled in the art, are alternately traversed by the products of combustion and the gas to be preheated.

The invention contemplates supplying coke-oven gas, that is to say gas of the kind that comes from the coking chamber and which is of high calorific value, to the same gas channels *e* which extend longitudinally beneath the heating flues *c*, which channels may thus serve as mixing chambers where the two kinds of fuel gas are mingled before entering the combustion flue. The means for admitting this gas of high calorific value constitutes also a valve mechanism for regulating or cutting off the flow of the low calorific gas from the passage *f*. Furthermore, this valve mechanism, as well as the means for controlling the flow of the high calorific gas, are operable from the tunnel *t*. Thus, a series of vertical openings or shafts *s* extend upward through the masonry from the tunnel *t* to each channel *e*, and in these openings are tubular members *p* which are provided at their upper ends with hollow valve portions *k*. These latter are preferably of refractory stone or other suitable heat-resisting material, and are mounted on the hollow stems *p* in any suitable manner. It will be understood that there is one of these valve members *p*, *k* for each of the twyer openings *d*, the valve member being disposed vertically beneath the latter so that by vertical adjustment each valve member controls the effective cross-section of the corresponding opening. By moving the valve members upward to the limit they completely close the twyer openings to passage of low calorific gas from the ducts *f*. At such time, however, or, if desired, when the valve members are adjusted to permit admission of more or less gas from the passages *f*, gas of high calorific power, such as coke-oven gas, may be supplied through the valve members themselves and through the openings *d* into the combustion flues. In the preferred construction there is a longitudinal gas main *n*, suitably supported by a hanger *r* in the upper part of the tunnel *t*, this main being suitably connected with a source of gas of the kind indicated and having a plurality of opposite branches *m* controlled by valves *l*. Vertical pipes *m'* project upward from the branches *m* and are connected by telescopic joints *r* with the lower ends of the tubular stems *p*. Any suitable means may be provided for holding these stems *p* and their valve members *k* at the desired adjustment and for permitting or effecting variation of such adjustment. In the illustrative construction shown the stems *p* pass slidably through removable

sockets *w* mounted on suitable supports *x* and having set screws *z* for engagement with said stems. By loosening these set screws the stems *p* may be raised and lowered, so as to effect corresponding adjustment of the valve members *k*, and thereafter the set screws are tightened to hold the desired adjustment.

From the foregoing description it will be understood that the combustion or heating flues *c* may be supplied with only one kind of fuel gas, that is to say, with the valve members *k* in the position shown in Fig. 1 and with the valves *l* closed, the combustion flues will receive gas only from the passages *f*. By opening the valves *l* the combustion flues will obviously be supplied with both kinds of gas, and it will further be apparent that by adjusting the valve members *k* to the desired height and by regulating the degree of opening of the valves *l* the proportions and amounts of the two kinds of gases may be exactly regulated. If the valve members *k* are moved up as far as they will go and valves *l* are opened, the combustion flues will be supplied with fuel gas only from the main *n*. When both kinds of fuel gas are being utilized simultaneously it will be observed that they are mingled in the channels *e* and twyer openings *d* before entering the combustion flue. Under such conditions the tubular members *k* act as nozzles delivering their jets of high calorific gas into the channels *e* in line with the openings *d*, with a consequent entraining or aspirating action on the low calorific gas in the channel.

What I claim as new is:

1. A coke-oven having heating walls containing combustion flues provided with means for supplying them with air to support combustion and with means for supplying them with one kind of gaseous fuel, in combination with members for regulating the quantity of such gaseous fuel thus supplied, and means for supplying a different kind of gaseous fuel to the combustion flues by way of said members when desired.

2. A coke-oven having a heating wall with a combustion flue therein, passages for supplying said flue with air to support combustion, and a fuel gas channel communicating with said flue by an opening, in combination with a hollow valve member extending into said channel and adapted to coöperate with said opening and connected with another source of fuel gas which it may supply to the combustion flue through said opening either simultaneously with or independently of the gas supplied to said channel.

3. In a coke-oven, the combination with a coking chamber, a tunnel below the same, combustion flues in the heating walls of the oven, and means for supplying said flues with air and fuel gas respectively, of an up-

- wardly-extending valve member operable from said tunnel for regulating the supply of said fuel gas, and means in said tunnel for supplying a different kind of fuel gas through said valve member.
4. In a coke-oven, the combination of a coking chamber, a vertical combustion flue at one side thereof, a gas channel beneath said flue and communicating therewith by one or more openings through the bottom of the flue, passages at opposite sides of the lower part of said flue, one for air and the other for fuel gas, the former communicating with the flue above the bottom thereof and the latter communicating with said gas channel, tubular members extending upward into said channel and provided with valve portions to coöperate with said openings, and a separate fuel gas supply connected 20 with the lower ends of said tubular members.
5. A coke oven having a coking chamber with a heating wall containing a combustion flue, a chamber communicating with said combustion flue, a longitudinal gas-supply channel communicating with said chamber, and gas-supply members entering said chamber and serving to control the communication between the same and the combustion flue.
6. A coke oven having a coking chamber with a heating wall containing a combustion flue, a chamber communicating with said combustion flue, a longitudinal gas-supply channel at one side of and communicating with said chamber by openings along its length, and gas-supply members entering said chamber from below and serving to control the communication between the same and the combustion flue.
7. A coke oven having a coking chamber with a heating wall containing a combustion flue, a chamber communicating with said combustion flue, a longitudinal gas-supply channel communicating with said chamber, gas-supply members entering said chamber and serving to control the communication between the same and the combustion flue, and means for admitting air directly to the flue to burn either or both kinds of gases.
8. A coke-oven having vertical combustion flues in its side walls provided with air and gas supply passages, in combination with an elongated longitudinally adjustable valve member for controlling the admission of gas from said gas supply passage to the combustion flue, said member being hollow, and a separate gas supply system including a pipe connected with said member by a telescopic joint.
9. In a coke-oven, the combination with a coking chamber, a combustion flue at one side thereof, and means for admitting air to said flue, of a fuel gas channel communicating with the lower part of said flue, a gas
- passage for supplying fuel gas of one kind to said channel, and piping for admitting fuel gas of a different kind to said channel.
10. In a coke-oven, the combination with a coking chamber, a combustion flue at one side thereof, and means for admitting air to the flue, of means for supplying fuel gas of one kind to the flue, a duct for supplying another kind of gas thereto acting as a valve to regulate the supply of the first-mentioned kind of gas, and valved connections for controllably supplying said duct with its different kind of gas.
11. A coke-oven having a coking chamber with a heating wall containing a combustion flue, a chamber communicating with said combustion flue by an opening, means for admitting one kind of fuel gas to said chamber, a nozzle connected with a different source of fuel gas and adapted to deliver into said chamber in line with said opening simultaneously with the admission of the first-mentioned kind of fuel gas to the chamber, and means for admitting air to the combustion flue to burn the mingled fuel gases which enter through said opening.
12. A coke-oven having a coking chamber, a side wall combustion flue, and means for supplying air to support combustion therein, in combination with a chamber communicating with said flue by an opening, means for conducting fuel gas of one kind to said chamber, and separate means for supplying fuel gas including a nozzle in said chamber delivering in line with said opening and adapted to be adjusted longitudinally with reference thereto.
13. A coke oven having a coking chamber with a heating wall containing a combustion flue, a mixing chamber separate from said flue but communicating therewith, separate means for admitting two different kinds of fuel gas to said mixing chamber, and means for supplying air to support combustion.
14. In a coke furnace heated by a mixture of coke furnace gas and blast furnace or other poor gas the combination of a retort, a vertical heating flue in the wall of the retort, a conical mixing chamber at the base of said heating flue, a conduit adapted to supply heated poor gas to said mixing chamber, a conduit adapted to supply unheated coke furnace gas to the mixing chamber, a tapered nozzle forming the end of said conduit and coöperating with the conical mixing chamber to form a valve for the poor gas supply and a conduit adapted to supply the air to support combustion also communicating with the heating flue.
15. In a coke furnace heated by a mixture of coke furnace gas and blast furnace or other poor gas, the combination of a retort, a heating flue in the wall of the retort, a mixing chamber adjacent to said heating flue and communicating therewith, a conduit

adapted to supply unheated coke furnace gas to said mixing chamber, a conduit adapted to supply heated poor gas to the mixing chamber, valves controlling said conduits, and a conduit adapted to supply air to support combustion also communicating with said heating flue.

16. In a coke furnace heated by a mixture of coke furnace gas and blast furnace or other poor gas, the combination of a retort, a vertical heating flue in the wall of the retort, a conical mixing chamber at the base of said heating flue, a conduit adapted to supply heated poor gas to said mixing chamber, a conduit adapted to supply unheated coke furnace gas to each of said mixing chambers, a tapered nozzle forming the end of each of said conduits and coöperating with the respective mixing chambers to form regulatable valves for the poor gas supply, means for altering the position of each nozzle relatively to its mixing chamber, valves controlling the supply of coke furnace gas, and a conduit adapted to supply air to support combustion also communicating with the heating flues.

17. In a coke furnace heated by a mixture of coke furnace gas and blast furnace or

other poor gas, the combination of a retort, a plurality of vertical heating flues in the walls of the retort, a conical mixing chamber at the base of each of said flues, a conduit adapted to supply heated poor gas to said mixing chambers, a plurality of conduits each adapted to supply unheated coke furnace gas to each of said mixing chambers, a tapered nozzle forming the end of each of said conduits and coöperating with the respective mixing chambers to form regulatable valves for the poor gas supply, means for altering the position of each nozzle relatively to its mixing chamber, valves controlling the supply of coke furnace gas, and a conduit adapted to supply air to support combustion also communicating with the heating flues.

In testimony whereof, I have signed my name to this specification, in the presence of two subscribing witnesses.
